UNITED STATES PATENT OFFICE.

JAMES H. RAND, OF NEWTON, MASSACHUSETTS

HINGED INDEX-FRAME

1,034,647.

Specification of Letters Patent. Patented Aug. 6, 1912.

Application filed October 18, 1911. Serial No. 655,417.

To all whom it may concern:

Be it known that I, JAMES H. RAND, a citizen of the United States, and resident of Newton, in the county of Middlesex and State of Massachusetts, have invented new and useful Improvements in Hinged Index-Frames, of which the following is a specification.

This invention relates to indexes of the kind comprising a support or stand upon which are pivotally mounted swinging frames or leaves for displaying the classified subject matter of the index; and the invention consists more particularly in the construction of the hinge member, and the means for securing the hinge member to the swinging frame.

In the accompanying drawings, which illustrate one embodiment of the invention,—Figure 1 is a perspective view of an index containing the invention, partly broken away; Fig. 2 is an enlarged detail view, showing in side elevation the upper corner of the swinging frame and upper hinge member; Fig. 3 is a similar view of the lower corner of the frame and lower hinge member; Fig. 4 is a section on line 4—4 of Fig. 2; and Fig. 5 is a section on line 5—5 of Fig. 3.

A represents the support or bracket on which the other parts are mounted, and B, B, represent the swinging frames or leaves. Plates a having a number of bearing holes for the hook-like hinge members b are secured to the support A in the usual manner. The frames A are preferably made of sheet metal and have the marginal upturned flanges b' and the inwardly turned lips b², forming with the body of the frame an inwardly facing channel. Index cards or strips d suitably inscribed, according to the matter to be classified, are held in the frame with their ends in the side channels of the frame. The parts thus far described may be substantially as heretofore employed.

It has been the practice hitherto to solder the hinge members b to the outside of the frames, and the present invention has to do principally with improving the connection between the hinge members and the frames. To this end I have invented devices best illustrated in Figs. 2 to 5 inclusive. The hinge member b is made with a relatively long and narrow shank b³, which is preferably of the same width and depth as the marginal channel of the frame. The shank

b³ is lodged within the channel against the flange b' with the hinge part b projecting from the edge of the frame as shown. On the side of the shank b³ opposite the flange b' is the notch or recess b⁴, the sides or ends of which furnish shoulders to be engaged by a holder secured to the frame to hold the hinge member in place. This holder, as herein shown, consists of a flat sheet metal plate c secured to the body of the frame by rivets or eyelets c', and having an upturned flange c² which fits into the recess b⁴ of the shank b³. The depth of the recess b⁴ is preferably the same as the thickness of the flange c² so that the flange shall not project outward beyond the lip b², with the result that the flange c² as well as the shank b³ are wholly contained within the channel, thus leaving a clear space within the marginal lips b² for the index cards. And as the body of the holder, c, is of thin, flat material, the holder c will permit the index cards d to overlie it without material interference or bulging.

With the construction above described the hinge member will be securely held and locked in position without the use of solder, requires little skill easily and quickly to assemble the parts, and furnishes a securement for the hinge member much stronger, more reliable, and handsomer in finish than has heretofore been employed.

I claim:

1. A swinging frame having an upturned flange and an inwardly turned lip forming with the body of the frame a channel, a hinge member lying in said channel, and a holder member secured to the frame and engaging said hinged member adapted to hold said hinge member against lateral movement out of said channel, and also to hold said hinge member positively locked against being moved lengthwise of said channel.

2. A swinging frame having a flange, a hinge member lying against said flange and provided with a retaining shoulder, and a holder member secured to the frame and engaging said shoulder to hold said hinge member in place.

3. A swinging frame having an upturned flange and an inwardly turned lip forming with the body of the frame a channel, a hinge member lying in said channel provided with a recess in its side, and a holder member of sheet material secured to the

body of the frame and having an upturned flange lodged within said recess.

4. A swinging frame having an upturned flange and an inwardly turned lip forming with the body of the frame a channel, a hinge member lying in said channel of a width not greater than the depth of the channel and provided with a recess in the side, and a holder member of sheet material

secured to the body of the frame and having an upturned flange lodged within said recess, and within said channel.

Signed by me at Boston, Massachusetts, this 11th day of October, 1911.

JAMES H. RAND.
